RICHARD T. CARLSON, OF ROSEDALE, KANSAS

COIL-UNIT AND SPARK-PLUG TESTER.

1,835,219.

Specification of Letters Patent. Patented Mar. 30, 1920.

Application filed August 5, 1918. Serial No. 248,321.

To all whom it may concern:

Be it known that I, RICHARD T. CARLSON, a citizen of the United States, residing at Rosedale, in the county of Wyandotte and 5 State of Kansas, have invented certain new and useful Improvements in Coil-Unit and Spark-Plug Testers, of which the following is a specification.

My invention relates to electro testing apparatus and while it may be used to advantage in testing various kinds of electrical devices it is more particularly adapted for testing the efficiency of spark plugs and vibrator coils used in the ignition systems of 15 automobiles.

In order that the invention may be fully understood, reference will now be made to the accompanying drawings, in which:

Figure 1 is a side elevation of the testing 20 apparatus with a vibratory coil in position to be tested.

Fig. 2 is a plan view of the parts disclosed by Fig. 1.

Fig. 3 is a front elevation of the parts 25 disclosed by Fig. 1, with the upper portion of the apparatus in cross section.

Fig. 4 is a diagram of the apparatus circuit and the vibrator coil circuit connected for operation.

In carrying out the invention, I employ a 30 suitable container 1 in which the cells of a primary battery 2 are located. The upper portion of said container 1 is provided with a tool box 4 and a handle 5 removably-secured in place by set screws 7 and 8, respectively, so that said tool box 4 and handle 5 may be readily removed preparatory to placement and removal of the battery cells. The upper portion of the tool box 4 is provided with a sliding cover 9 which may be 35 easily opened, so that access can be had to the interior of said box 4.

12 and 13 designate two contacts secured to the container 1. The contact 13 is permanently connected to one end of the primary circuit 15, while the contact 12 is connected to a manually controlled switch 17, adapted to be thrown in and out of engagement with a contact point 18 at the opposite end of the primary circuit 15. The contacts 40 12 and 13 consist, preferably, of spring metal to insure a firm bearing against certain contacts hereinafter described on the vibrator coil C. The container 1 is also pro-

vided with an electrode 20 and a conductor 55 21, which latter is provided at one end with a pivot 22 upon which a movable conductor 24 is operably mounted. The electrode 20 is provided with a fixed conductor 26 adapted to coat with the conductor 21 in supporting 60 a spark plug B when the same is to be tested.

The vibrator coil C is removably-held in position at one end of the container 1 by the contacts 12 and 13 and an arm 29. The arm 29 is yieldably-held in engagement with the vibrator coil C by a coil spring 27 interposed between said arm 29 and a washer 28 at the outer end of a screw 30, which latter secures the arm 29 loosely at one side of the 70 container 1.

The vibrator coil C may be of the usual construction comprising a contact P', a post E to which said contact P' is connected by a wire conductor e, an adjustable screw F, a 75 contact G, a spring H provided at its free end with a piece of soft iron h, a core I, a primary coil J, a secondary coil K, a contact S³ connected to one end of the primary coil J and the secondary coil K, an electrode S² 80 connected to the opposite end of the secondary coil K, a condenser N connected to the post E and the spring support M, and a conductor O connecting the support M and one end of the primary coil J.

In practice the vibrator coil C is placed in 85 position for testing at one end of the container 1 with the contacts P' and S³ in engagement with the contacts 12 and 13, and the electrode S² opposite the electrode 20. 90 On closing the switch 17 the exciting current flows from the primary circuit 15 and passes through said switch 17, contacts 12 and P', the conductor e, the post E, the adjustable screw F, the contact G, the spring H, the wire O, primary coil J, contacts S³ 95 and 13, and back to the circuit 15. The foregoing circuit energizes core I, which attracts the soft iron h and breaks the contact at G. The current then ceases to flow, 100 core I loses its magnetism and the reaction of the spring H closes the contact at G, thus reestablishing the circuit. These operations are repeated in rapid succession and result in constantly changing the magnetism in the 105 core I and thereby inducing in the secondary coil K a high E. M. F. which flows through the contacts S³ and 13, the elec-

trode 20, jumps the spark gap to the electrode S^2 and returns to the secondary coil K.

By observing the intensity of the spark at the gap between the electrodes 20 and S^2 , an attendant can readily determine whether or not the soft piece of iron h is adjusted in proper relation to the adjacent end of the core I, to obtain the highest efficiency from the vibrator coil, because if said soft iron h is adjusted too far or too close to the core I the spark across the gap will diminish accordingly. All necessary adjustments can be readily made in the usual manner with the screw F.

15 In testing a spark plug B, the same is placed in position upon the conductors 21 and 26 and the movable conductor 24 is swung downward between the electrodes 20 and S^2 , as disclosed by Fig. 4. When testing the spark plug B the vibrator coil C is left in position on the container 1 and the circuits are, substantially, the same as when testing the vibrator coil C alone, excepting that said spark plug B and the conductor 24, 20 in connection with the conductors 21 and 26 provide a metallic path for the secondary current, and hence the same instead of jumping the comparatively wide gap between the electrodes 20 and S^2 jumps the narrow gap 25 between the electrodes of the spark plug, so that the condition of the latter can be readily determined by the intensity of the spark across the last-mentioned electrodes.

From the foregoing description it is apparent that I have produced a testing apparatus embodying the advantages above pointed out, and while I have shown and described the preferred form of apparatus, I reserve the right to make such changes in 35 the construction, proportion and arrangement of parts as properly fall within the spirit and scope of the claims.

Having thus described my invention, what

I claim and desire to secure by Letters Patent, is:

1. In a testing apparatus, the combination 45 with a vibrator coil and a spark plug, of a primary circuit, contact members at the ends of said circuit for engagement with certain contact members of the vibrator coil, an electrode in the primary circuit spaced from an electrode of the vibrator coil to leave a spark gap, a conductor in circuit with the primary circuit electrode and adapted to support one end of the spark plug, a second conductor 50 spaced from the first one and adapted to support the opposite end of the spark plug, and a movable conductor in circuit with said second conductor and arranged to be adjusted into engagement with the vibrator 55 coil electrode to shunt the circuit from the spark gap and through the spark plug.

2. In a testing apparatus, a container, a battery within said container, an arm yieldably mounted upon said container, a spring 60 contact mounted on the container and spaced from said arm, a switch in circuit with said contact, a switch point in circuit with one pole of the battery, a contact in circuit with the opposite pole of the battery, an electrode in circuit with the last-mentioned contact, a conductor connected to said electrode and adapted to support one end of a spark plug, a conductor spaced from the last-mentioned one and adapted to coact therewith 65 in supporting the spark plug, and a movable conductor operably-connected to the last conductor and adapted to be moved in front of the electrode.

In testimony whereof I affix my signature 70 in the presence of two witnesses.

RICHARD T. CARLSON.
